His Attorney.

UNITED STATES PATENT OFFICE

2,065,350

COMPRESSOR FOR REFRIGERATING MACHINES

Christian Steenstrup, Schenectady, N. Y., assignor to General Electric Company, a corporation of New York

Application August 26, 1933, Serial No. 686,959

11 Claims. (Cl. 230—206)

5 My invention relates to compressors for refrigerating machines, and more particularly to an arrangement for separating oil and compressed refrigerant discharged from the compressor.

It is an object of my invention to provide a compressor for refrigerating machines having an oil separator which shall be of simple construction and effective in operation.

10 Another object of my invention is to provide an improved arrangement of an oil separator and a compressor casing or the like.

15 Further objects and advantages of my invention will become apparent as the following description proceeds, and the features of novelty which characterize my invention will be pointed out with particularity in the claims annexed to and forming a part of this specification.

20 For a better understanding of my invention, reference may be had to the accompanying drawing in which Fig. 1 is a sectional view of a refrigerating machine embodying my invention, and Fig. 2 is a sectional view on the line 2—2 of Fig. 1.

25 Referring to Fig. 1, I have shown a refrigerating machine including a closed motor and compressor casing 10 within which is arranged a driving motor 11 and a compressor. The compressor has a crank-shaft 12 which is connected by piston rods 13 to pistons 14 arranged in

30 cylinders 15, formed in a block 16 in the walls of the casing 10. The stator of the motor includes suitable windings 17 arranged in a core structure 18 secured in contact with the walls 35 of the casing 10 and the rotor of the motor is mounted on the end of the crank-shaft 12. The crank-shaft is journaled in a bearing 19 and in a bearing plate 20 secured to the casing 10 by bolts 21. A crank-pin 22 is provided on the end 40 of the crank-shaft 12 beyond the bearing plate 20.

45 In order to lubricate the compressor, the crank-pin 22 is arranged to drive an oil pump piston 23 operating in an oscillating cylinder 24 and journaled in a bearing 25 in the bearing plate 20. The cylinder 24 is provided with a port 26 which registers with an intake port 27 during the intake stroke of the piston 23, oil being drawn up through a tube 28 from a body of oil 29 in the bottom of the casing 10 during 50 the intake stroke. A screen 30 prevents particles of foreign matter from entering the oil pump. During the exhaust stroke, the port 26 of the cylinder 24 registers with an exhaust port (not shown) and forces the oil out into the lubricating passages of the compressor, which are

arranged within the shaft and in the bearings in a manner well known in the art. Cylinder 24 is provided with a flat surface seated on the bearing plate 20 and is held against the bearing plate by a spring 31 arranged between the bearing 25 and a retainer 32 on a trunnion 33 of the cylinder 24. Gas is drawn into the casing 10 through a suction conduit 34 and enters the cylinders 15 through intake ports controlled by spring-pressed valves 35 in the tops of the pistons 14, the cranks 10 of the pistons being arranged 180 degrees apart on the shaft 12. Gas compressed in the cylinders 15 is exhausted through discharge ports 36 in the heads of the cylinders and enters a chamber formed by securing a dome 37 by bolts 38 to 20 the block 16 above the cylinders 15. Compressed gaseous refrigerant is discharged into the dome 37 and flows from the dome through a connection 39 into a condenser comprising a plurality of helically wound tubes 40 connected between 25 upper and lower manifolds 41 and 42, respectively. The dome 37 and the condenser are enclosed in a shell 43 forming a water jacket which is secured by bolts 44 to an annular shoulder 45 on the walls of the casing 10. Cooling water is 30 admitted to the lower portion of the shell 43 through a connection 46 and is directed upwardly over the tubes 40 by a cylindrical baffle 41. The water then flows over the top of the baffle 47, around the dome 37 and also around the block 16. 35 The water is withdrawn from the casing 43 through an annular cooling jacket 48 arranged about the motor 11, as is clearly shown in Fig. 2. After passing through the jacket 48 the water passes out through a connection 49. The gaseous 40 refrigerant cooled by circulating water is liquefied in the condenser and flows out through a connection 50 and a conduit 51 to a receiver or float-valve chamber 52 from which it flows in regulated quantities through a conduit 53 to a header 54 of 45 a flooded evaporator 55. The evaporator is provided with sinuous tubes 56 connected to the header below the level of liquid refrigerant indicated at 54a for the circulation of liquid refrigerant, and refrigerant vaporized in the evaporator 55 by absorption of heat from the chamber to be cooled is withdrawn from the header 54 through the suction conduit 34 by the compressor in the casing 10.

50 In refrigerating systems of the type herein described a portion of the lubricant in the compressor cylinders mixes with the compressed refrigerant and is discharged from the cylinders. It is desirable to separate the oil from the refrigerant before admitting the refrigerant to the 55

evaporator in order to prevent an accumulation of oil in the evaporator, which would decrease the efficiency thereof. I provide a device arranged within the dome into which gas is discharged from the compressor for separating the oil and the refrigerant which are discharged, and for returning the oil to the compressor casing whenever a predetermined quantity is collected in the separator.

10 Referring again to Fig. 1, I have shown an upright cup 57 opening away from the discharge ports arranged within the dome 37 and supported on the block 16 by a connection 58 through which the oil collected in the separator is returned to 15 the casing 10, as hereinafter described. The cup 57 is spaced from the walls of the dome 37 and is provided with an out-turned rim 59 having openings 60 to allow passage of compressed refrigerant and oil. Cup 57 is preferably made of 20 copper or any other suitable material of high thermal conductivity in order to permit ready dissipation of heat from the cup to the walls of the dome 37 which is cooled by the water circulating thereover. The compressed gas containing 25 oil which is discharged from the compressor through the ports 36 enters the dome 37 below the cup 57 and passes upwardly between the cup and the dome where it is substantially cooled and passes through the openings 60 and impinges 30 against a downwardly projecting annular baffle 61 formed in the upper wall of the dome 37 and which projects below the rim of the cup. The cooling of the compressed gas, together with its impact against the sides of the openings 60 and 35 against the baffle 61 causes the oil to separate from the gas and to collect in drops which fall to the bottom of the cup 57. The end of the connection 39 is secured to the dome 37 by a joint including a nut 62 in the threaded member 40 63, and a screen 64 mounted between disks 65 is secured to the lower end of the member 63 which is arranged entirely above the lower edge of the baffle 61 and prevents foreign particles from passing into the condenser and also further tends 45 to separate any oil which may remain in the gas.

In order to return the oil collected in the cup 57 to the casing 10, I provide a valve 66 mounted in the upper end of the connection 58 and 50 connected to be operated through links 67 and 68 by a float 69. The link 67 is pivoted to the valve 66 at 70 and to the link 68 at 71, and the link 68 is pivoted to an L-shaped bracket 72 at 73. The bracket 72 comprises a support for the float 55 mechanism and is secured to the cup 57 together with the connection 58 by a nut 74 threaded on the connection 58 within the cup 57. The float 69 is mounted to move vertically on a shaft 75 secured to the cup and L-shaped member at 76. 60 When a predetermined amount of oil collects in the bottom of the cup, the float 69 will rise and lift the valve 66 to allow a quantity of the oil to flow through an opening 76 in the side of the connection 58 and to flow downwardly through 65 the connection 58 and a passage 77 in the block 16, back to the body of oil 29 in the bottom of the casing 10. The oil accumulating in the cup 57 is returned to the compressor casing in this manner as the compressor maintains the pressure in the dome 37 considerably above the pressure in the compressor casing 10.

In the operation of the refrigerating system shown in Fig. 1, refrigerant gas compressed in the cylinders 15 is discharged through the ports 75 36 into the dome 37, which is cooled by water cir-

culating within the casing 43. The gas is cooled as it passes between the cup 57 and the dome 37, and the force of the impact against the rim of the cup and against the baffle 61, together with the turbulent circulation produced by the sudden 5 change in direction of the flow of the gas when it reaches the top of the dome and must pass downwardly around the baffle 61, causes any oil which is contained in the gas to be separated out and to collect in the bottom of the cup 57. Gas 10 then passes out through the screen 64 and the connection 39 to the condenser tubes 40 where it is cooled and liquefied by the circulation of cooling water flowing into the casing 43 through the connection 46. The liquefied refrigerant 15 then flows down through the conduit 51 to the receiver 52 from which it is delivered in regulated quantities through the conduit 53 to the header 54 of the evaporator 55. Since the oil has been separated from the gas within the dome 20 37, a body of oil does not collect within the evaporator 54 and thereby decrease the capacity and efficiency of the evaporator. The evaporator 55 is located within the chamber to be cooled and upon absorbing heat from the chamber the liquid 25 refrigerant within the evaporator is vaporized and collects in the header 54 from which it is withdrawn through the conduit 34 by operation of the compressor. When a predetermined amount of oil has collected within the cup 57, 30 the float 69 rises and lifts the valve 66 from its seat in the connection 58 and thereby allows the oil to return through passage 77 to the casing 10.

From the foregoing it is evident that I have 35 provided a compact refrigerating machine having an oil separator which is of simple construction and is effective in operation.

While I have described my invention as embodied in a compression refrigerating system, 40 other applications will readily be apparent to those skilled in the art, and I do not desire my invention to be limited to the specific invention shown and described, and I intend in the appended claims to cover all modifications within 45 the spirit and scope of my invention.

What I claim as new and desire to secure by Letters Patent of the United States is:

1. A compressor casing having a discharge opening therein, means secured to said casing 50 and including a chamber having an inlet over said discharge opening for receiving compressed gas having liquid particles entrained therein, means including a cup arranged in said chamber and having walls spaced from the walls of said chamber for separating the liquid particles from the gas and for collecting the liquid particles, and means including a valve arranged in said cup for removing said liquid from said chamber.

2. A compressor casing having a discharge 60 opening, means secured to said casing and including a chamber having an inlet over said discharge opening for receiving compressed gas from said compressor, means including a cup arranged in said chamber and having walls spaced from the 65 walls of said chamber for separating liquid from the gas and for collecting the liquid, said cup having an annular rim extending toward the walls of said chamber, an annular baffle secured to the upper wall of said chamber and extending with in the rim of said cup, means including a float arranged in said cup for removing liquid collected in said cup from said chamber, and means for withdrawing compressed gas from said chamber.

3. A compressor including a closed casing hav-

ing a cylinder block in the walls thereof, means including a chamber having walls secured to the walls of said casing for receiving compressed gas from said compressor, means including a cup

5 arranged in said chamber and having walls spaced from the walls of said chamber for separating lubricant from the gas discharged from said compressor and for collecting the lubricant, means including a float arranged in said cup for

10 removing said lubricant from said cup, means for discharging gas from said chamber, and means including a closed shell surrounding said chamber for circulating water around said chamber to cool said chamber and said cylinder block.

15 4. A compressor casing having a discharge opening therein for compressed gas having liquid particles entrained therein, means secured to said casing over said opening and including a chamber for receiving said compressed gas from said

20 casing, means including a cup arranged in said chamber and having walls spaced from the walls of said chamber for separating the liquid particles from said compressed gas and for collecting the liquid particles, said compressed gas being

25 discharged into said chamber below said cup, and means for removing the liquid collected in said cup.

5. A compressor casing having a discharge opening therein for compressed gas having liquid

30 particles entrained therein, means secured to said casing over said opening and including a chamber for receiving said compressed gas from said casing, means including a cup arranged in said chamber and having walls spaced from the walls

35 of said chamber for separating the liquid particles from said compressed gas and for collecting the liquid particles, said compressed gas being discharged into said chamber below said cup, and means for removing the liquid collected in said

40 cup and for returning said liquid to said casing.

6. A compressor casing having a discharge opening therein for compressed gas having liquid particles entrained therein, means secured to said casing over said opening and including a

45 chamber for receiving said compressed gas from said casing, a cup arranged within said chamber above said discharge opening and opening away from said discharge opening, means including an out-turned rim on said cup engaging the walls of

50 said chamber and having a plurality of spaced openings therein for separating liquid particles from said compressed gas whereby said liquid is collected in the bottom of said cup, means for removing liquid from said cup, and means for

55 withdrawing compressed gas from said chamber.

7. A compressor casing having a discharge opening therein for compressed gas having liquid particles entrained therein, means secured to said casing over said opening and including a chamber

60 for receiving said compressed gas from said casing, a cup arranged within said chamber above said discharge opening, and opening away from said discharge opening, means including an out-turned rim on said cup engaging the walls of said

65 chamber and having a plurality of spaced openings therein for separating liquid particles from said compressed gas whereby said liquid is collected in the bottom of said cup, means for remov-

ing liquid from said cup and for returning said liquid to said casing, and means for withdrawing compressed gas from said chamber.

8. A compressor casing having a discharge opening therein for compressed gas having liquid particles entrained therein, means secured to said casing over said opening and including a chamber for receiving said compressed gas from said casing, a cup arranged within said chamber above said discharge opening and opening away from said discharge opening, means including an out-turned rim on said cup engaging the walls of said chamber and having a plurality of spaced openings therein for separating liquid particles from said compressed gas whereby said liquid is collected in the bottom of said cup, a shell secured to said casing and surrounding said chamber, means admitting cooling fluid to said shell for cooling said chamber and said casing, and means for withdrawing compressed gas from said chamber.

9. A compressor casing having a cylinder block, a cylinder head secured to said cylinder block and having a discharge port therein, means including a chamber having walls secured to said cylinder block and surrounding said cylinder head for receiving from said discharge port compressed gas having liquid particles entrained therein, means including a cup arranged in said chamber for separating liquid particles from said compressed gas and for collecting said liquid, means for removing said liquid from said cup, and means for withdrawing compressed gas from said chamber.

10. A compressor casing having a cylinder block, a cylinder head secured to said cylinder block and having a discharge port therein, means including a chamber having walls secured to said cylinder block and surrounding said cylinder head for receiving from said discharge port compressed gas having liquid particles entrained therein, a cup arranged within said chamber above said cylinder head and opening away from said cylinder block, means including an out-turned rim on said cup engaging the walls of said chamber and having a plurality of spaced openings therein for separating liquid particles from the said compressed gas and for collecting said liquid in the bottom of said cup, means for removing said liquid from said cup, and means for withdrawing compressed gas from said chamber.

11. A compressor casing having a cylinder block, a cylinder head secured to said block and having a discharge port therein, means including a chamber having walls secured to said block and surrounding said cylinder head for receiving from said discharge port compressed gas having liquid particles entrained therein, means including a cup arranged in said chamber for separating liquid particles from said compressed gas and for collecting said liquid, means for removing liquid from said cup and for returning said liquid to said casing, a shell secured to said casing and surrounding said chamber and said block, means admitting cooling fluid to said shell for cooling said chamber and said block, and means for withdrawing compressed gas from said chamber.

CHRISTIAN STEENSTRUP.
